MULTIPLE FUSE PLUG

Maurice Lefebvre, Detroit, Mich.

Application December 19, 1933, Serial No. 703,089

2 Claims. (Cl. 200—125)

This invention relates to multiple fuse plugs and the object of the invention is to provide a multiple fuse plug so arranged that in case a fuse is blown the device may be re-set to bring another fuse into the circuit.

Another object of the invention is to provide a multiple fuse plug comprising a plug member and a cap member, the cap member being detachable from the plug member and turnable to different positions to bring different fuses into the circuit.

A further object of the invention is to provide a multiple fuse plug having a series of fuse elements, the fuse elements being stamped from one piece of sheet metal with the different members extending radially from the central portion thereof.

Another object of the invention is to provide a multiple fuse plug adapted to be threaded into a socket and arranged so that the device may be set to bring different fuse elements into the circuit without the necessity of removing the fuse plug from the socket.

These objects and the several novel features of the invention are hereinafter more fully described and claimed and the preferred form of construction by which these objects are attained is shown in the accompanying drawing in which—

Fig. 1 is an elevation of a multiple fuse plug embodying my invention.

Fig. 2 is an enlarged section taken on line 2—2 of Fig. 1.

Fig. 3 is a section taken on line 3—3 of Fig. 2.

Fig. 4 is a section taken on line 4—4 of Fig. 2.

Fig. 5 is a plan view of the one piece multiple fuse element.

Fig. 6 is an enlarged plan view of the multiple fuse plug.

As shown more particularly in Fig. 1, the fuse plug 1 is formed from insulating material such as glass, hard rubber or other suitable material. A threaded sheet metal casing 2 is mounted on the plug 1 and a lead 3 extends from the mem-

ber 2 to a contact 4 provided in a shallow circular recess formed in the top of the plug. A contact screw 5 is provided, having ribs 6 fitting in slots 7 in the plug 1 and this screw is provided with a semi-spherical head 8 which forms the contact for the bottom of the socket. The contact screw 5 extends upwardly through the plug and through a recess shown in Fig. 2 and the upper end is arranged to extend through a central aperture in a cap 10. The inner face of this cap is provided with a central recess and with

a series of wedge shaped raised portions 11 which form radial grooves between the wedge shaped portions into which the ends 12 of the fuse element may be positioned. This fuse element, as shown in Fig. 5, comprises a central portion 13 and a series of radially extending portions 12 and the fuse elements are each provided with a narrow portion 14 between the ends 12 and the central portion 13. This portion 14 provides the fuses which may have any desired capacity. This fuse element is positioned in the cap 10, as shown in Fig. 3, with the central portion 13 of the fuse element positioned in the central recess of the cap and with the radially extending ends 12 extending through the grooves 15 between the raised portions 11. The raised portions 11 are circular in general outline and are arranged to fit within the peripheral flange 15 which provides a shallow recess at the top of the fuse plug.

A spring 16 is positioned within the recess in the plug 1 and this spring, at the lower end, engages a collar 25 on the contact screw 5 so as to make electrical contact therewith and this spring at the upper end engages a washer 17 and tends to force the same into contact with the central portion 13 of the fuse to make electrical contact therewith. When the device is assembled, the cap 10 is positioned over the contact screw 5 with the fuse element 12a engaging the contact 4 of the outer threaded casing 2, as will be understood from Figs. 2, 3 and 4. The plug is also provided with a raised rib member 18 which engages in the groove 19 of the cap which is diametrically opposite the fuse element 12a. With this rib 18 engaged in the groove 19, it is impossible to turn the cap in relation to the fuse plug and insures the fuse element being held in proper position in respect to the contact 4. A nut member 20 of insulating material is then threaded onto the upper end of the contact screw 5 and as it is turned down, it insures proper contact between the fuse element 12 and the contact 4.

At this time, the fuse plug may be threaded into a socket. The current will then flow from the threaded casing 2 of the fuse plug through the lead 3 to the contact 4 and thence through the fuse element 12a and through the narrow portion 14 of the fuse element to the central portion 13 thereof from which point, the current may flow directly to the contact screw 5 or through the washer 17 and spring 16 to the screw 5 thus completing the circuit. Should the fuse blow out, it is only necessary to un-

thread the nut member 20 from the end of the screw 5 to allow the cap to be lifted and indexed one-eighth of a turn to bring the next fuse element into position for use, at which time, the 5 nut 20 may be again tightened to insure proper electrical contact between the parts and to lock the cap on the rib 18 to prevent its turning. If desired, the cap 10 and nut member 20 may be made of glass so that it will be easy to see 10 whether the fuse is blown or not.

From the foregoing description, it becomes evident that the device is very simple and efficient in operation, will not easily get out of order, is composed of few parts and is of consequent low manufacturing cost and provides a 15 device which accomplishes the objects described.

Having thus fully described my invention, its utility and mode of operation, what I claim and desire to secure by Letters Patent of the United 20 States is—

1. In a multiple fuse plug, a threaded plug member having a circular recess at the top, a contact fixedly positioned in one side of said recess and a lug extending into the recess diametrically opposite the contact, a cap member having a circular portion adapted to be positioned in said recess, the circular portion of the cap being provided with a central recess and a series of grooves opening radially therefrom, a 25 fuse element having a central portion fitting in said central recess and having a series of fuse members formed integrally therewith and extending radially therefrom and positioned in the radial grooves of the cap, the arrangement being

such that when the cap is positioned on the plug member, the lug of the plug member extends into one of the radial grooves of the cap and the fixed contact of the plug member extends into another radial groove of the cap and into contact with the fuse member therein, a central contact member extending through the plug and cap, a nut threadable onto the central contact member to secure the cap to the plug member and electrical contact means between 10 the central contact member and the central portion of the fuse element.

2. In a multiple fuse plug, a threaded plug member having a circular recess at the top, a contact fixedly positioned in one side of said recess and a lug extending into the recess diametrically opposite the contact, a cap member having a circular portion adapted to be positioned in the recess of the plug member, the circular portion of the cap being provided with 20 a central recess and a series of grooves opening radially therefrom, a fuse element having a central portion fitting in the central recess and having a series of fuse members formed integrally therewith and extending radially therefrom 25 and positioned in the radial grooves of the cap, the arrangement being such that when the cap is positioned on the plug member the lug of the plug member extends into one of the radial grooves of the cap and one of the fuse members 30 contacts the fixed contact and means for securing the cap to the plug member.

MAURICE LEFEBRE.
